UNITED STATES PATENT OFFICE.

WALTER GUY PYLE, OF TOPEKA, KANSAS.

CREAM-EXTRACTOR.

1,288,987.

Specification of Letters Patent. Patented Dec. 24, 1918.

Application filed April 18, 1918. Serial No. 229,404.

To all whom it may concern:

Be it known that I, WALTER G. PYLE, citizen of the United States, residing at Topeka, in the county of Shawnee and State of Kansas, have invented certain new and useful Improvements in Cream-Extractors, of which the following is a specification, reference being had therein to the accompanying drawings.

10 This invention relates to a cream extractor, and has for its object the simplification of means for extracting cream from a bottle and also to produce a new and efficient device for accomplishing the purpose just specified.

15 With this and other objects in view the invention consists of certain novel constructions, combinations and arrangement of parts as will be hereinafter fully described and claimed.

20 In the drawings:

Figure 1 is a view in side elevation of a device constructed in accordance with the present invention showing the same partly in the upper part of a milk bottle.

25 Fig. 2 is a view in side elevation, at right angles to the line upon which Fig. 1 is viewed.

Fig. 3 is an enlarged vertical sectional view of the device.

30 Fig. 4 is a top plan view of the device.

Fig. 5 is a perspective view of the plunger and the parts fixedly secured thereto.

Fig. 6 is a bottom plan view of the device.

35 Fig. 7 is a horizontal sectional view taken on the line 7—7, Fig. 3, and looking in the direction of the arrows.

Referring to the drawings by numerals, 1 designates the body or container, and 2, the top or cap thereof.

40 The body 1, has an annular horizontal flange 3, formed upon its lower end constituting part of the bottom, and a central aperture 4. Across the aperture 4 is secured the guiding bar or plate 5, which bar 5 is 45 provided with a central aperture 6.

The cap or cover 2, is provided with a central opening 7, which opening or aperture 7 registers with the aperture 6, in the bar 5 at the bottom of the body or container 1, 50 Fig. 3. Integral with the top 2, is a cylindrical extension 8, and this extension 8 has its lower end attached to a transverse strip 2^a, which strip 2^a is a part of cap 2. The strip leaves sufficient space on either side of

the same (see Figs. 1 and 4) to facilitate the 55 cleaning or washing of the cap 2.

The cylindrical extension 8 is provided with elongated, registering apertures or slots 9, in which the horizontal portion 10, of the grip device slides; at the outer ends of 60 the horizontal portion 10 of the grip device, are loops 11, in which the operator places his fingers for actuating the device. Integral with the horizontal portion 10, is plunger rod 12, and fixedly secured to plunger 65 rod 12, just above the horizontal portions 10 of the grip device, is the follower-disk 13, which disk 13 is engaged by the lower end of the coil spring 14; the coil spring 14 being mounted upon the upper or inner end of the 70 plunger 12 (Fig. 3), and the upper end of the coil spring 14 bears against the peculiarly constructed thumb rest 15, hereinafter described.

The lower end of the plunger rod 12 is 75 pointed as at 16, for facilitating the positioning of the lower end in aperture 6; carried near the lower end 16 is a valve disk 17, that normally closes the opening 4 in the bottom of the body 1.

80 My thumb rest 15 comprises a curved body that is placed at an angle to the longitudinal axis of the loops 11, and horizontal portion 10 (Figs. 1, 2 and 4), so that when the operator places two fingers in the loops 10, the thumb will rest in a natural position against the thumb rest 15 as has been discovered from actual experiment with a device constructed in accordance with the present invention. Upon the thumb rest 15, and at 90 one of its ends, is formed a curved, sharpened end portion 18, to be used in removing the caps from the milk bottles.

95 It is a fact that when milk is delivered in milk bottles the upper part of the milk is cream, as a rule, and if a person desires to pour off the cream then about one-half the poured liquid is cream and half is milk. Now, by using my improved device, only the 100 cream need be extracted from the bottle, for by placing the fingers in loops 11, and the thumb in thumb rest 15, raising the plunger and its coöperate parts to the position shown in dotted lines in Fig. 3, then inserting the device in the milk bottle as shown in Fig. 1, only the cream need be permitted to enter the body or container 1, and upon all of 105 the cream having entered the body 1, the

operator can release the loops 11 and permit the valve disk 17, to be seated through the action of spring 14, and then the device can be removed from the milk bottle and placed 5 over cups or any suitable receptacle, and by raising the plunger and the valve disk 17, the cream can be discharged at the will of the operator.

I wish it to be understood that I reserve 10 the right to make minor changes or alterations in the construction of my device as fairly fall within the scope of the appended claim.

What I claim is:

- 15 In a device of the class described, the combination with a body provided with a horizontal flange upon its lower end, and with an opening, a bar provided with a central aperture secured to said horizontal flange, a 20 cap mounted upon said body, said cap provided with a transverse strip extending across the same, said strip provided with a central aperture registering with the aperture of said bar, a cylindrical extension integral with said strip, said extension provided 25 with parallel slots, a thumb rest integral

with the upper end of said cylindrical extension, a plunger rod normally positioned in the apertures of said strip and said bar, a valve disk secured to the plunger near its 30 lower end, said disk resting against the inner face of said horizontal flange, the lower end of said plunger being sharpened for the insertion thereof in the aperture of said bar, a finger device secured to said plunger, said finger device comprising a horizontal portion extending through the parallel slots of said cylindrical extension, said horizontal portion provided at its ends with integral loops, a follower disk secured to the plunger above 40 the horizontal portion of said finger device, and a coil spring on the inner end of said plunger, and engaging, at its inner end, the follower disk, and engaging at its outer end, the thumb rest. 45

In testimony whereof I hereunto affix my signature.

WALTER GUY PYLE.
